Attorney

UNITED STATES PATENT OFFICE.

DOCTOR L. COOPER, OF NEWTON, MISSISSIPPI.

ROLL-PAPER HOLDER AND FEEDER.

Application filed April 25, 1925. Serial No. 25,831.

This invention relates to an improved paper holding and feeding device particularly adapted for holding a roll of paper to be utilized in facilitating the taking of orders or notes given by phone call or personal callers.

My primary aim is to provide an improvement upon a similar device of this kind shown and described in an application filed 10 by me on August 31, 1923, and designated by Serial No. 660,282, the same having been allowed and matured into Patent 1,539,994, June 2, 1925, and the present application being a continuation in part thereof. Reference being had to the prior application, it will be observed that one feature of novelty is the provision of a base upon which an upright is mounted, this upright being of a predetermined width and having vertically extending flanges formed on its opposite vertical edges, the inner faces of the flanges being constructed to provide bearings for journals of a paper holding roll, and there being a supplemental paper tension and guiding roll rotatably mounted between the lower portions of the flanges at a point beneath the paper holding roller, so that the paper from the lastnamed roller may be trained around and beneath the 20 guiding roll, in a manner to dispose it between the adjacent portions of the flanges and to permit these flanges to function additionally for confining the paper therebetween.

35 The improvement embodied in the present case resides more particularly in the manually actuated rollers mounted in a series upon the upper side of the base, the free end of the paper being passed between these rollers which are arranged in a manner to facilitate movement of the paper therebetween. An advantage is derived by supporting two of these rollers upon a removable U-shaped bracket, which in turn carries a hood extending over the rollers and affording a tearing knife.

Other features and advantages of the invention will become apparent from the following description and drawing.

40 In the accompanying drawing, forming a part of this application, and in which like numerals are employed to designate like parts throughout the same:

45 Figure 1 is a side elevation of a paper holder constructed in accordance with the present invention.

Figure 2 is a front elevation of the same, and

Figure 3 is an enlarged central longitudinal section, taken approximately upon the 60 plane of the line 3—3 of Figure 2.

Referring to the drawing in detail, it will be seen that the reference character 1 designates an inclined base provided on its bottom with appropriate rests 2. It will be noted that the forward portion of this base is relatively wide, while the rear portion terminates in a reduced extension 3. Rising from this extension and being of a width corresponding thereto is an upright 4, the upper end of which is fashioned to render it ornamental and to permit it to be fastened to a support if desired. Integral with the opposite vertical edges of this upright and with the opposite longitudinal edges of the extension 3 are forwardly extending side flanges 5 of the approximate configuration shown. In their inner faces and adjacent the top, these flanges are provided with inclined feet 6 adapted for reception of the journals 7 on the ends of a paper holding roller 8. Pivoted to the flanges beneath this roller is a U-shaped wire guide 9, through which the free end portion of the paper is passed. Disposed beneath the paper roller is a supplemental roll 10, which may be distinguished as a paper guiding and tensioning roller. It should be noted that this last named roller is disposed substantially beneath the journals of the paper holding 90 roller, and that the free end portion 11 of the paper is brought downwardly and between the lower portions of the flanges and thence beneath the roller to permit the flanges to have the additional functions of 95 confining and guiding the paper therebetween.

100 Mounted upon the major portion of the base are the feeding rollers before referred to. In this connection, attention is directed to Figure 3, wherein it will be seen that a transverse recess 12 is formed in the upper side of the base, there being a roller 13 located in this recess and mounted for rotation in appropriate journals. One of the journals may be extended to accommodate a turning handle 14 as shown in Figure 2. Located above this roller 13 is an arched or substantially inverted U-shaped bracket 15, which is of a width to serve as a mounting 105 for a pair of spaced parallel auxiliary rollers 16. These rollers are disposed in close

spaced proximity to the exposed upper surface of the roller 13 so as to afford sufficient space for passage of the free end portion of the paper. The presence of these additional rollers greatly facilitates the feeding and movement of the paper. Carried by the bracket 15 is a hood 17, including a downwardly inclined front wall 18 having a serrated edge 19, serving as a tearing knife 10 for the paper. The hood also includes a depending rear wall 20, which is disposed so as to not interfere with the free movement of the paper.

As shown, the device may embody pivoted retaining clips 21 for maintaining the journals of the paper holding roller in place, a note receiving hook 22 and appropriate clips for suspension of pencils and the like.

It is thought that by considering the description in connection with the drawing, persons familiar with devices of this class will be able to obtain a clear understanding of the same. Therefore a more lengthy description is thought unnecessary.

While the preferred embodiment of the invention has been shown and described, it is to be understood that minor changes coming within the field of invention claimed 30 may be resorted to, if desired.

I claim:

In a paper holder of the class described, a base provided in its upper side with a transverse recess, a feed roller located in

said recess and journaled for rotation upon the base and having the upper portion of its periphery projecting above the surface of the base, a substantially inverted U-shaped bracket disposed longitudinally over the recess, the free ends of the arms of said inverted U-shaped bracket being disposed laterally and secured on the top of the base adjacent the respective ends of the recess, a pair of auxiliary feed rollers journaled for rotation in the bracket between the arms 45 thereof, said auxiliary feed rollers being disposed on opposite sides of the first mentioned feed roller and adapted for cooperation therewith, and a hood associated with the bracket, the same being formed of a 50 relatively wide strip of metal which is bent to provide an intermediate and end portions, the intermediate portion of the hood being secured on the crown portion of the inverted U-shaped bracket, the forward end of the 55 strip of metal forming the hood extending downwardly adjacent the forwardmost auxiliary feed roller, the lower edge of the forward end being serrated to provide a tearing knife for the free end of a strip of 60 paper which is adapted to be fed between the first mentioned feed roller and the auxiliary feed rollers, the rear end portion of the strip being disposed downwardly adjacent the rearmost auxiliary feed roller.

In testimony whereof I affix my signature.

DOCTOR L. COOPER.
